(57) **CLAIM**

The ornamental design for a tire as shown and described.

DESCRIPTION

FIG. 1.1 is a front view of a tire showing our new design; FIG. 1.2 is a first enlarged partial view of FIG. 1.1; FIG. 1.3 is a second enlarged partial view of FIG. 1.1; FIG. 1.4 is left perspective view of FIG. 1.1; FIG. 1.5 is a first enlarged partial view of FIG. 1.4; FIG. 1.6 is a second enlarged partial view of FIG. 1.4; FIG. 1.7 is a left view of FIG. 1.1; FIG. 1.8 is a right perspective view thereof; FIG. 1.9 is a first enlarged partial view of FIG. 1.8; FIG. 1.10 is a second enlarged partial view of FIG. 1.8; and, FIG. 1.11 is a right view of FIG. 1.1. The broken lines in FIG. 1.1, FIG. 1.4 and FIG. 1.8 are demarcations of the portion of the design visible in the enlarged partial views of FIG. 1.2, FIG. 1.3, FIG. 1.5, FIG. 1.6, FIG. 1.9 and FIG. 1.10, and form no part of the claimed design.

1 Claim, 11 Drawing Sheets
